UNITED STATES PATENT OFFICE.

BERNHARD DREYFUS, OF NEW YORK, N. Y.

DESIGN FOR A CURTAIN-BAND.

SPECIFICATION forming part of Design No. 12,066, dated December 21, 1880.

Application filed November 1, 1880. Term of patent 14 years.

To all whom it may concern:

Be it known that I, BERNHARD DREYFUS, of the city, county, and State of New York, have invented a new and Improved Design for 5 Curtain-Bands, of which the following is a specification.

Figure 1 is a face view of my newly-designed curtain-band; and Fig. 2 is a view of a portion of the band in enlarged size, showing the de-10 tails more clearly.

My invention relates to bands for holding curtains, drapery, and masks, for which purpose heretofore cords and bands formed of gimp have been used.

15 A is the band, the piled surface of which is formed of tufts *a*, and *b* is the binding-cord, formed with loops *c* at the ends of the band for convenience of use. This fabric is made on a frame by hand, and is generally similar 20 to what is known as "frame-work." The tufts

are held and bound together by diagonal warps shown at *d*, the tufts being cut on the surface of the fabric to complete the work. The material I prefer to use is worsted in any variety or combination of color, by which I obtain a 25 highly-ornamental effect and harmony of color between the bands and curtains. The general shape of the band, as shown, is that of a double lanceolated figure; but I do not limit myself in that respect.

Having thus described my invention, I claim 30 as new and desire to secure by Letters Patent—

The design for curtain-bands herein shown and described, consisting of tufts *a*, tied by diagonal warps *d*, with the edge of the band 35 provided with a cord, *b*.

BERNHARD DREYFUS.
